By His Attorney # UNITED STATES PATENT OFFICE.

EDWARD J. BIRKETT, OF MILWAUKEE, WISCONSIN, ASSIGNOR TO THE MILWAUKEE HARVESTER COMPANY, OF SAME PLACE.

METAL WHEEL.

SPECIFICATION forming part of Letters Patent No. 636,890, dated November 14, 1899.

Application filed July 25, 1898. Serial No. 686,885. (No model.)

To all whom it may concern:

Be it known that I, EDWARD J. BIRKETT, a citizen of the United States, residing at Milwaukee, in the county of Milwaukee, in the 5 State of Wisconsin, have invented certain new and useful Improvements in Metal Wheels, of which the following is a specification.

My invention relates to improvements in metal wheels of the suspension type, in which 10 the strain upon the spokes is in the direction of their length; and its object is to provide a means for securing the spokes to the hub or hubs that will be strong and simple in construction and efficient in its mode of operation. I attain this object by the mechanism 15 illustrated in the accompanying drawings, in which—

Figure 1 is a vertical section of the wheel. Fig. 2 is an end view of one of the hubs. Fig. 20 3 is an end view of the other hub. Fig. 4 is a cross-section of Fig. 3. Fig. 5 is the axle-thimble. Fig. 6 is an end view of the smaller end of Fig. 5. Fig. 7 is a side view of the 25 wheel complete. Fig. 8 is a modified manner of forming the spoke. Fig. 9 is a detail section of other parts.

Like numerals refer to like parts throughout the several views.

1 is the inner hub, provided with a transverse opening in the center adapted to receive the axle-thimble 2. The axle-thimble is provided with a collar portion 2', to which may be fitted the central opening of a gear or sprocket wheel 3, and is also provided with a 35 larger collar portion 2'', provided with a tooth 2''', that fits into a receptacle in the sprocket-wheel for the purpose of securing the two members against independent angular movement.

40 4 is the outer hub and is provided at its center with a transverse opening adapted to receive the outer end of the axle-thimble, the said outer end of said thimble being provided with a fluted portion 5, adapted to receive the internal projecting portion 6 of the hub 4, the said internal projecting portions having different lengths, as shown in Fig. 4, for the purpose of increasing or diminishing the outward adjustment of the hubs upon the 45 axle-thimble.

50 7 are spokes provided with heads at their

outer ends and having their inner ends formed with a portion at approximately right angles with the body portion and adapted to pass through the openings provided for their reception in the wheel-hubs. The transverse bent portion of the spoke is preferably provided with a shoulder portion 7', formed by cutting away a portion of the material in an angular direction at the inner side of the bent 55 end, as shown in Fig. 9, or it may be formed by making a short reverse bend in the material, as shown in Fig. 8, and the openings in the hubs being made of a greater length radially to receive them.

8 are the lags or tread-pieces, secured in place by the heads of the spokes. The spokes are passed through the openings in the tread-pieces and the corresponding openings in the rim of the wheel, and their inner ends are 60 hooked into the transverse openings in the wheel-hubs in the manner shown in Fig. 9. The axle-thimble is then passed through the central opening in said hubs from left to right, the internal projecting lip portions 6 fitting 65 into the flutes upon the axle-thimble, one of said flute portions being made shorter than the others and provided with a shoulder portion adapted to receive the abutting end of the internally-projecting lip portion 6. The 70 sprocket or gear wheel 3 being placed in position upon the inner end of the axle-thimble, resting against the annular collar 2'', bolts are passed through openings in said wheel and corresponding openings in the inner 75 wheel-hub and said hub is drawn toward the annular collar 2'' and the outer hub 4 is forced in the opposite direction, giving a proper tension to the spokes in a well-known manner, and the distance between the hubs may 80 be increased or diminished, with a corresponding degree of tension upon the spokes, by changing the position of the thimble in relation to the lip portions 6 on the hub 4.

What I claim as my invention, and desire 85 to secure by Letters Patent, is—

1. In a metal wheel the combination of a rim having apertures for the reception of spokes; spokes headed at their outer ends and having a portion of their inner ends bent at approximately right angles with their longitudinal length and provided with a shouldered or

notched portion; said shouldered or notched portion being upon the side of the inner bent end most remote from the longitudinal portion, hubs or disks adapted to receive the bent ends of the spokes and engage with the notched or shoulder portion of said spokes when the said hubs are moved apart.

2. In a metal wheel the combination of an axle-thimble adapted to receive two annular disks or hubs, means for moving the disks in opposite directions upon the thimble; spokes headed at their outer ends and having a portion of their inner ends bent approximately at right angles to their longitudinal portion and provided with a notch forming a shoulder, said notch being upon that side of the inner bent end most remote from the longitudinal portion, said hubs being adapted to receive the inner ends of the spokes when said spokes are at right angles with the axis of the wheel and to engage with the notched portion of said spokes when the hubs are moved outward.

3. A metal-wheel spoke formed with a head and having a portion of its opposite end bent

at approximately right angles to its longitudinal length in the form of a hook, and having an indentation in said hook portion, said indentation being upon the side of the hook portion most remote from the longitudinal portion, substantially as and for the purpose described.

4. In a metal wheel the combination of an axle-thimble, hubs movable thereon adapted to receive the spokes and means for forcing them apart; spokes formed with a portion at their inner ends that will be approximately parallel with the axis when the spoke in its longitudinal length is at right angles with said axis, said inner ends being provided with a shoulder portion upon the side most remote from the longitudinal portion, adapted to engage with the hub as the spoke is moved outward and its inner end thereby caused to change from a parallel to an angular relation with the axis.

EDWARD J. BIRKETT.
